C. O. WILLIAMS.
CAR DOOR FASTENER.
APPLICATION FILED JULY 10, 1916.

1,243,025.

Patented Oct. 16, 1917.

UNITED STATES PATENT OFFICE.

CHARLES O. WILLIAMS, OF KANSAS CITY, MISSOURI.

CAR-DOOR FASTENER.

1,243,025.

Specification of Letters Patent. Patented Oct. 16, 1917.

Application filed July 10, 1916. Serial No. 108,422.

To all whom it may concern:

Be it known that I, CHARLES O. WILLIAMS, a citizen of the United States, residing at Kansas City, Missouri, have invented 5 a certain new and useful Improvement in Car-Door Fasteners, of which the following is a full, clear, and exact description, such as will enable others skilled in the art to which it appertains to make and use the 10 same.

This invention relates to car door fasteners, and has for its main object to provide a fastener for freight car doors which comprises as an essential part thereof an 15 indicating or counting mechanism that is actuated every time the door is unlocked.

Another object is to provide a fastener of the character described, in which either a key-controlled lock or an ordinary car seal 20 may be utilized to lock the door in its closed position.

Still another object is to provide a fastener of the character described, in which means is provided by which the number of 25 pieces of freight that are loaded into or unloaded from the car can be accurately counted. Other objects and desirable features of my invention will be hereinafter pointed out.

30 Figure 1 of the drawings is a front elevational view of a car door lock constructed in accordance with my invention.

Fig. 2 is a similar view, with the cover plate or protective housing removed.

35 Fig. 3 is a horizontal sectional view, taken approximately on the line 3—3 of Fig. 1.

Fig. 4 is a vertical sectional view, taken on the line 4—4 of Fig. 1.

Fig. 5 is a horizontal sectional view, taken 40 on the line 5—5 of Fig. 1; and.

Fig. 6 is a detail sectional view, showing certain parts of the fastener in the position assumed when the door is being unlocked.

Briefly described, my invention consists 45 in coöperating elements arranged on the car door and the car body, means for locking said elements together and for unlocking the same and a counting mechanism that is actuated every time said locking means is 50 actuated to unlock said members.

Referring to the drawings, A designates 55 a portion of a freight car door, and B designates a portion of the car body or door frame to which the door is adapted to be fastened. In the preferred form of my invention as herein shown, the fastener con-

sists of a hasp or member C that is pivotally and slidably connected to the door A, and which is adapted to coöperate with a grooved or headed stud D secured to the door frame 60 B, when the door is in its closed position. The hasp C is provided with a central opening 1 that is adapted to pass over the stud D, and a vertically-movable plate 2 is arranged over said opening, said plate having 65 therein a key hole slot 3, the enlarged portion of said slot being of sufficient size to pass fully over the stud D, and the reduced portion of said slot being adapted to coöperate with the groove 4 in said stud, so 70 as to prevent outward movement of the hasp member when said plate is in a certain position. The plate 2 is provided in one of its side edges with a notch 5 that coöperates with the bolt 6 of a key-controlled lock 7, 75 so that said plate can be held locked in the position shown in Fig. 2, wherein the reduced portion of the key hole slot is in engagement with the groove 4 of the stud D.

It is obvious from the foregoing description that when the parts are in the position shown in Fig. 2, the door A will be securely locked to the frame B, the plate 2 being in such a position that the hasp cannot be moved outwardly to disengage the same 80 from the stud D, and the bolt 6 preventing upward movement of said plate, so as to hold the enlarged portion of the key hole slot opposite said stud.

Means is provided for indicating the vertical movements of the plate 2, which lock and unlock the hasp member C, said means as herein shown consisting of a counter or accumulator 8 which is actuated by said plate at each upward movement thereof, the 90 actuating means comprising a depending arm 9 secured to the operating shaft of the accumulator and a coöoperating notch 10 in the plate 2. Whenever the plate 2 is moved upwardly vertically to position the enlarged portion of the key hole slot 3 opposite the stud D so that the hasp C can be moved outwardly away from the frame B, the arm 9, by reason of its being confined in the slot 10, will be moved or rocked a distance 100 sufficient to register a new unit in the accumulator 8. After the plate 2 has been moved upwardly so that said hasp can be moved outwardly away from the stud D, said plate is held in its raised position by 105 means to be hereinafter described, so that when the door is again locked, the enlarged

portion of the slot 3 will aline with the opening 1 and be in a position to pass over the head of the stud D. When the hasp and plate have passed over the head of the stud, the plate 2 is moved downwardly, either 5 manually or by the force of gravity, so that the reduced portion of the slot 3 again engages the groove 4 of the stud, this downward movement restoring the arm 9 of the 10 accumulator to the position shown in the drawings where it is in readiness to register an additional unit on the accumulator on the next upward movement of the plate 2.

By utilizing a counter or accumulator in 15 conjunction with my improved fastener, I am enabled to keep an accurate record of the opening and closing of the door. For example, a car is shipped into a station and the reading of the accumulator is taken. 20 The car door is then opened, the local freight removed and the door again locked. This locking and unlocking registers one unit on the accumulator. The station agent keeps a record of the number on the accumulator when he receives the car and a record 25 of the number when the car is checked out from his station. If, in the car's journey from his station to the next, the door is opened by any unauthorized person, the fact 30 will be shown by the accumulator, whose reading will conflict with the reading of the last station agent. Thus, the railroad company is enabled to trace the approximate point on the road where the car was broken into, namely, between the two stations whose 35 accumulator readings conflict.

Another very desirable feature of using 40 an accumulator in conjunction with the fastener is the fact that a station agent can utilize the accumulator to check up accurately the number of pieces of freight which are being loaded into or unloaded from the car.

As previously stated, the hasp member C 45 is pivotally connected and also slidably mounted on the door A, the particular construction consisting of a headed pin or bolt 11 that cooperates with a longitudinally-extending slot 12 in the hasp C. The inner 50 end of the slot 12 is offset slightly at 13 and a semi-cylindrical, thickened portion 14 partially surrounds said offset portion. When it is desired to use the accumulator as a counter for the number of pieces of freight 55 that are being unloaded from the car, the door is unlocked, and the hasp C moved longitudinally of the bolt 11, so as to position the openings 1 and 3 in the hasp and plate 2, respectively, over a stud D' similar to the 60 stud D. The offset portion 13 of the slot 12 is then positioned under the head of the bolt 11, the thickened portion 14 preventing outward movement of the hasp with respect to 65 said bolt and holding the hasp rigidly in the position shown in broken lines in Fig. 1.

The plate 2 may then be actuated or reciprocated manually each time an article of freight is removed from the car, and thus show on the accumulator the exact number of pieces of freight that are unloaded. 70

A protective housing 15 is preferably arranged over the working parts of the fastener, said housing being secured to the hasp in any suitable manner, as by means of studs or rivets 16 and provided on its lower side 75 with a cut out portion for the passage therethrough of the plate 2 (see Fig. 5). The means for guiding the lower end of the plate 2 in its vertical movements consists of a rectangular lug 17 on the plate 2 that cooperates 80 with an inverted U-shaped guiding portion 18 on the housing 15, and the means for guiding the opposite end consists of a shouldered screw or pin in the hasp C that cooperates with a vertically-disposed slot 20 in 85 the plate 2; as shown clearly in Figs. 2 and 4.

As previously stated, means is provided for retaining the plate 2 in its raised position when said plate has been lifted to unfasten the door, the means herein shown consisting of a spring-actuated plunger 21 that bears on the stud D when the door is in its locked position, but which moves inwardly into the enlarged portion of the key hole slot 3 whenever the hasp is moved outwardly 95 away from the stud D, as shown in Fig. 6, thus preventing said plate from moving downwardly until the plunger is retracted by coming into contact with one of the studs D or D'. The plunger 21, as herein shown, 100 consists of a cylinder that is guided in a barrel 22 secured to the housing 15, and the spring 23 which actuates said plunger is preferably fastened to said housing and said plunger so that said plunger will not become 105 detached from said barrel when in its operative position shown in Fig. 6. I wish it to be understood, however, that I do not limit myself to the exact form of plunger-operating means described, as various other means 110 could be employed for actuating said plunger without departing from the spirit of my invention.

If desired, a seal 24 may be employed to 115 prevent the plate 2 from being moved upwardly to clear the stud D, said seal being passed through alining slots 25 in the lug 17 and guideway 18, as shown in Figs. 4 and 5.

When the car is traveling under seal, 120 means is provided for indicating whether or not the key-controlled bolt 6 is in its locked or unlocked position, said means consisting of a plate 26 carried by said bolt, said plate being provided with a portion 27 having different colors thereon which are exposed 125 through a sight opening 28 in the housing 15, said opening being approximately half the width of the portion 25, so that only one color will be visible at a time. The housing is also provided with a sight opening 29 in 130

alinement with the accumulator and an opening 30 in alinement with the key hole of the lock 7.

From the foregoing description it will be seen that I have provided a car door fastener by the use of which a car door can be securely locked against entrance by an unauthorized person, which registers an accurate record of the opening and closing of the door, thus enabling the railroad company to keep a close check on the car, and which can be conveniently utilized for counting articles of freight that are to be loaded into or removed from the car.

Having thus described my invention, what I claim, and desire to secure by Letters Patent, is:—

1. In a car door fastener, a fixed member on the door frame, a coöoperating member on the door, means for locking said members together, a key-controlled bolt for retaining said members in locked position, a housing that covers said locking means and bolt, and which is provided with a sight opening, and means carried by said bolt and visible through said sight opening for indicating the condition of said key-controlled bolt.

2. In a car door fastener, a hasp pivotally mounted on the door and provided with a circular opening, a headed stud on the door frame, a plate slidably mounted on said hasp and provided with a key hole slot, the smaller portion of which is adapted to lie under the head of said stud so as to prevent outward movement of said hasp with re-

spect to said stud, a housing that substantially incloses said plate, and a spring-pressed plunger carried by said housing that is adapted to enter the enlarged portion of the key hole slot whenever said hasp is moved outwardly from said stud.

3. In a car door lock, a hasp pivotally mounted on the door, a headed stud on the door frame, a vertically-movable plate mounted on said hasp and provided with a key hole slot that coöperates with said stud, said slot being of such dimensions that when the plate is in its raised position the enlarged portion of said slot will pass freely over the head of said stud, and when said plate is in its lowered position, the reduced portion will lie under the head of said stud and thus prevent outward movement of said plate with respect to said stud, and means for holding said plate in its raised position when it is moved outwardly away from said stud.

4. In a car door fastener, a movable member on the door, a rigid member on the door frame, a plate slidably mounted on said movable member that coöperates with said rigid member to hold said members in engagement, said plate being provided with a notch, a counter on said movable member provided with an operating shaft, and an arm on said shaft that projects into said notch, so that movement of said plate will be recorded in said counter.

CHARLES O. WILLIAMS.
